(73) Assignee: **Mitsumi Electric Co., Ltd.**, Tokyo (JP)

CLAIM

(**) Term: **14 Years**

(21) Appl. No.: **29/155,870**

The ornamental design for an optical disk recording reproduction apparatus, as shown and described.

(22) Filed: **Feb. 21, 2002**

DESCRIPTION

(30) **Foreign Application Priority Data**

Aug. 21, 2001 (JP) 2001-024440

(51) LOC (7) Cl. **14-01**

FIG. 1 is a perspective view of the top, front, and right side of an optical disk recording reproduction apparatus showing our new design;

(52) U.S. Cl. **D14/260.1**

FIG. 2 is a perspective view of the bottom, rear, and left side thereof;

(58) Field of Search D14/156, 217,

FIG. 3 is a front elevational view thereof;

D14/239, 260, 260.1, 262, 299; 360/104-105,

FIG. 4 is a rear elevational view thereof;

114; 369/244-247, 263-264, 266

FIG. 5 is a right side elevational view thereof;

(56) **References Cited**

FIG. 6 is a left side elevational view thereof;

U.S. PATENT DOCUMENTS

FIG. 7 is a top plan view thereof;

D367,278 S * 2/1996 Moriwaki et al. D14/260.1
D389,150 S * 1/1998 Tanaka D14/156

FIG. 8 is a bottom plan view thereof; and,

FIG. 9 is a view similar to FIG. 1 with the drawer extended.
